US0D1095166S

(12) **United States Design Patent** (10) **Patent No.:** **US D1,095,166 S**
(45) **Date of Patent:** **** Sep. 30, 2025**

(54) **FRUIT STORAGE BOX**

(71) Applicant: **Zijun Yang**, Ulanqab (CN)

(72) Inventor: **Zijun Yang**, Ulanqab (CN)

(**) Term: **15 Years**

(21) Appl. No.: **29/992,131**

(22) Filed: **Mar. 6, 2025**

(51) **LOC (15) Cl.** **09-07**

(52) **U.S. Cl.**

USPC **D7/628**

(58) **Field of Classification Search**

(57) **CLAIM**

The ornamental design for a fruit storage box, as shown and described.

DESCRIPTION

FIG. 1 is a front perspective view of a fruit storage box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the fruit storage box, which form no part of the claimed design.

1 Claim, 8 Drawing Sheets
